CLAIM

The ornamental design for a ceiling fan light kit, as shown and described.

DESCRIPTION

FIG. 1 is a top perspective view of a ceiling fan light kit in the environment of a ceiling fan, showing my new design; FIG. 2 is a bottom perspective view of the ceiling fan light kit in the environment of the ceiling fan of FIG. 1; FIG. 3 is a side view of the ceiling fan light kit in the environment of the ceiling fan of FIG. 1; FIG. 4 is a front view of the ceiling fan light kit in the environment of the ceiling fan of FIG. 1; FIG. 5 is a top view of the ceiling fan light kit in the environment of the ceiling fan of FIG. 1; and, FIG. 6 is a bottom view of the ceiling fan light kit in the environment of the ceiling fan of FIG. 1. Portions of the ceiling fan light kit and ceiling fan environment shown in broken lines form no part of the claimed design.
